UNITED STATES PATENT OFFICE.

WILLIS R. WHITNEY, OF SCHENECTADY, NEW YORK, ASSIGNOR TO GENERAL ELECTRIC COMPANY, A CORPORATION OF NEW YORK.

DASH-POT.

No. 827,339.

Specification of Letters Patent.

Patented July 31, 1906.

Application filed October 13, 1905, Serial No. 282,540.

To all whom it may concern:

Be it known that I, WILLIS R. WHITNEY, a citizen of the United States, residing at Schenectady, county of Schenectady, State of New York, have invented certain new and useful Improvements in Dash-Pots, of which the following is a specification.

This invention relates to pistons or the like to be used in connection with cylinders, and has for its object the improvement of devices of this character, so as to render them reliable and efficient under all conditions and at the same time cheap and durable.

More specifically, the invention relates to an improvement in pistons for use in connection with retarding devices commonly known as "dash-pots." In devices of this character it is essential in order to obtain a long and uniform time interval that the piston have a snug running fit in the cylinder. With uniform conditions it is not a difficult matter to make a cylinder and piston having a satisfactory fit. In practice, however, the conditions are constantly changing, due principally to changes of temperature. Upon a fall of temperature these dash-pots have heretofore been unreliable, since the difference in the contraction and expansion of the metals forming the cylinder and the piston causes them to stick. This matter is particularly troublesome in the case of dash-pots for use in arc-lamps, where a particularly uniform and reliable retarding device is required. Moreover, it is not sufficient that the expansion and contraction of the piston and cylinder be the same. Some provision must be made for lubrication, especially in the case of air dash-pots.

In carrying out my invention I provide a piston which is composed of substantially the same material as the cylinder, so as to give the same expansion coefficients. In addition to this I provide a self-lubricating bearing-surface between the piston and the cylinder. In this manner I provide against the sticking of the parts, due to the unequal expansion and contraction, and also provide for constant and uniform lubrication.

My invention further consists in the features of construction and the arrangement and combination of elements hereinafter set forth, and particularly pointed out in the claims annexed to and forming a part of this application.

In the drawings, Figure 1 is a sectional view of a dash-pot embodying my invention. Fig. 2 is a view of the piston of the dash-pot, the bearing-rings being in section; and Fig. 3 is a view of one of the split rings.

Referring to the drawings, 10 is a cylinder, preferably of some well-known metal, such as brass, open at one end for the insertion of the piston 11. The particular construction of this cylinder forms no part of my invention and may be any well-known type. In the construction shown the cylinder is closed at one end and is provided with a ball-valve, this being a type well known in the art. The piston 11 has a solid plunger-head 12, provided with end flanges 13 and 14. As a bearing-surface for this piston I provide a series of rings 15, of self-lubricating material, preferably graphite. The plunger 12 is preferably of the same material as the cylinder, and therefore has the same expansion coefficient. Upon changes of temperature therefore the cylinder and the plunger-head will expand or contract equally, and there will therefore be little or no binding between them. The rings 15 furnish the lubricant, and in order to allow for the expansion and contraction of the metallic parts these bearing-surfaces must be made yielding. This I accomplish by having the rings split, as at 16, so that the elasticity of the rings will allow them to contract and expand, as may be necessary.

In the drawings I have shown three split rings having the splits staggered to prevent leakage. The rings are originally made with an outer diameter a trifle smaller than the inner diameter of the cylinder and the inner diameter of the rings smaller than the outer diameter of the plunger with which they are to be used. The rings are then split in any desired manner—as, for instance, by being cut partially through from the outside and then ruptured by forcing a tight-fitting core into them. The rings are then assembled in a slightly extended or expanded form upon the core of the plunger, the amount of the expansion being just sufficient to make a snug running fit in the cylinder.

It will thus be seen that I have provided a dash-pot which will be absolutely reliable at all temperatures. The dash-pot and the plunger being of the same or similar metals will expand equally and the graphite will furnish the lubricant. I have made the lubri-

cating-surface expansible, so as to allow for these variations in a very simple manner, it being possible to slip the rings over the flange of the solid plunger-head, and in case of breakage they may readily be renewed.

5 While I have described my invention in connection with a specific self-lubricant and a particular form of construction for the bearing-surface, it should be understood that 10 I do not limit my invention in these particulars to what I have shown and described beyond the scope of the claims annexed hereto.

15 What I claim as new, and desire to secure by Letters Patent of the United States, is—

15 1. A dash-pot piston having a yielding bearing-surface of self-lubricating material.

20 2. A dash-pot piston having a rigid body portion and a yielding bearing-surface of self-lubricating material.

25 3. A dash-pot piston having a rigid body portion and a resilient bearing-ring of self-lubricating material.

4. A dash-pot piston comprising a metallic body portion and a yielding bearing-ring of graphite.

25 5. A dash-pot comprising a cylinder and a piston having substantially the same expansion coefficients, one of said parts having a self-lubricating bearing-surface.

30 6. A dash-pot comprising a metallic cylinder and a piston therefor having a metallic body portion and a yielding self-lubricating bearing-ring.

35 7. A dash-pot comprising a metallic cylinder and a piston therefor having a rigid body

portion and a bearing-surface composed of self-lubricating split rings.

8. A dash-pot comprising a metallic cylinder and a piston therefor having a metallic body portion and a self-lubricating bearing- 40 surface, said metallic parts having substantially the same expansion coefficients.

9. A dash-pot comprising a metallic cylinder and a piston therefor having a metallic body portion and a yielding self-lubricating 45 bearing-surface, said metallic parts having substantially the same expansion coefficients.

10. A dash-pot comprising a metallic cylinder and a piston therefor having a metallic body portion and a graphite bearing-surface, 50 said metallic parts having substantially the same expansion coefficients.

11. A dash-pot comprising a metallic cylinder and a piston therefor having a rigid metallic body portion and a bearing-surface 55 composed of self-lubricating split rings, said metallic parts having substantially the same expansion coefficients.

12. A dash-pot comprising a metallic cylinder and a piston therefor having a solid 60 metallic body portion and a bearing-surface composed of staggered graphite split rings, said metallic parts having substantially the same expansion coefficients.

In witness whereof I have hereunto set my 65 hand this 11th day of October, 1905.

WILLIS R. WHITNEY.
